UNITED STATES PATENT OFFICE.

JOHN A. SMITH, OF BELLEVUE, KENTUCKY, ASSIGNOR TO THE UNITED STATES ELECTRICAL TOOL COMPANY, OF CINCINNATI, OHIO, A CORPORATION OF OHIO

SNAP ELECTRIC SWITCH.

1,095,474

Specification of Letters Patent.

Patented May 5, 1914.

Application filed September 9, 1912. Serial No. 719,296.

To all whom it may concern:

Be it known that I, JOHN A. SMITH, a citizen of the United States, residing at Bellevue, in the county of Campbell and State of Kentucky, have invented certain new and useful Improvements in Snap Electric Switches, of which the following is a specification.

This invention deals with improvements in electric snap switches and is more particularly concerned with the type thereof adapted by finger pressure alternatively to open and close the circuit.

One object within the contemplation of this invention is to create a switch of the foregoing nature which will be notable for compactness, simplicity, durability and reliability.

Another object is to provide a finger snap switch well adapted for use in connection with portable electric motor driven apparatus and which may be readily constructed into a part of the apparatus in or adjacent a handle thereof within convenient reach for manipulation by the finger.

Another object is to devise a switch of the above specified type in which but one finger operated piece will suffice for throwing the switch by finger pressure, both for opening and for closing the circuit in alternative succession, and in which the contact springs alone will perform the office of snapping the movable switch element into the open or closed position and holding it in such position.

Other objects will be in part obvious from the annexed drawings, and in part indicated in connection with the following description.

In order that this invention may be made more readily comprehensible to those skilled in this art, drawings illustrating one of the many possible embodiments thereof have been appended as a part of this disclosure, and in such drawings, like characters of reference denote corresponding parts throughout all the figures, of which:

Figure 1 is an elevation showing a handle combined with a switch construction in accordance with this invention. Fig. 2 is an end view partly in section showing details of the connection between the finger operated piece and the rocking switch element. Fig. 3 is an inside elevation showing the arrangement of the contacting and operating springs.

Continuing now by way of a more detailed description, 1 indicates a portion of the casing of the apparatus embodying this invention, and 2 signifies a handle secured to said casing portion either integrally or by suitable screws as will be readily understood. Laterally projecting from said casing or handle is a portion 3 serving as a support or bearing face for the movable members of the switch. This portion is here shown provided with a hole extending parallel with the handle, and opening into the interior of the casing 1, and in such hole is arranged a rock shaft 4 terminating in a screw threaded end 5, to which is secured a block 6 of insulating material rigidly positioned by means of nuts 7. In this instance, this block of insulating material is square in outline, so as to provide two opposite facets of insulating material, and two other facets, to which are affixed contacting plates 8 and 9, that are electrically connected and held in place by means of connecting wires 10. Arranged at a distance from said insulating block is another insulating block 11, which is secured to the casing 1, and carries the spring members 12 and 13, that extend forwardly to the insulating block 6, and have their free ends resiliently urged against the same, as shown by Fig. 3. These spring members serve to snap the rock shaft, and the block of insulating material carried thereby into definite positions, either determining the opening or closing of the circuit, according to whether or not the contact plates 8 and 9 are in contact with the springs 12 and 13—such springs being also of conducting material, and forming current conveyers. For the purpose of enabling the insulating blocks 6 to be rocked into positions at ninety degrees apart, the pin 14 extends radially from said shaft and swings through an appropriate angle in a cavity or seat 15, provided by part 3. This part 3 is in turn bored transversely to the axis of the rock shaft, and in this bore is mounted a reciprocating finger piece 16, that has its ends projecting from either side of part 3. This finger piece is preferably provided with a slot 17 having an opening closely adjacent the rock shaft so as to provide abutments 18 and 19 adapted to contact opposite sides of the pin at a point closely adjacent its base. By reason of this construction, if the reciprocating plunger 16 be pressed and moved by the finger, the

shaft 4 will be quickly rocked until the pin 14 reaches an extreme position, which will be determined by its contact with some other part, as for example, by the contacting of 5 its upper end with the end walls of the slot 15 of the part 3. A suitable cap 20 may be used for inclosing these parts.

It will thus be perceived that this invention is well adapted to achieve the objects 10 and ends aforesaid by means of a simple and compact arrangement, and that the same will be durable and reliable for the purposes intended.

Without further elaboration, and in the 15 light of current knowledge, the foregoing disclosure will enable those skilled in this art to readily utilize various interchangeably available elements which, although perhaps calculated to appear widely different 20 from those shown, and have a somewhat varied disposition, would nevertheless embody certain, if not all of the herein described features which, from the aspect of the prior art, would constitute characteristics of this invention and should and accordingly are intended to be comprehended 25 within the wording and scope of the following claims.

I claim—

- 30 1. A finger actuated snap switch of the nature disclosed combining a support, a rock shaft mounted therein, electrical switch mechanism actuated by said rock shaft, a finger piece mounted to reciprocate trans- 35 versely to the axis of said rock shaft and having each end free whereby it may be moved in either direction by a pressure of the finger on a corresponding end, a pin projecting radially from said rock shaft, 40 and a pair of abutments carried by said finger piece and located on opposite sides of said pin near its base, whereby said pin may be swung through an arc during a reciprocation of said finger piece.
- 45 2. A finger actuated snap switch of the nature disclosed combining a support, a rock shaft mounted therein, electrical switch mechanism actuated by said rock shaft, a finger piece mounted to reciprocate trans- 50 versely to the axis of said rock shaft and having each end free whereby it may be moved in either direction by a pressure of the finger on a corresponding end, said finger piece being slotted intermediate its 55 ends, the end walls of said slots being relatively close on the side of the piece adjacent the rock shaft and widely spaced at the opposite side of the piece, and a pin radially

extending from said rock shaft into said slot.

3. In a device of the nature disclosed, a tool casing, an external support, a rock shaft extending from the support to the interior of the casing, a member on the inner end of the rock shaft having alternate insulating 65 and metallic contact surfaces, springs within the casing between which said member reciprocately rocks, said springs and contact surfaces being formed to impart a snap movement to the rock shaft after its initial, 70 manually-induced movement, means establishing an electric circuit when said metallic and spring surfaces are in contact, and means on the support having transmission connections for reciprocately rocking said 75 shaft.

4. In a device of the nature disclosed, a tool casing, an external support, a shaft ex- 80 tendsing from said support to the interior of the casing, a member on the inner end of said shaft having alternate insulating and metallic contact surfaces, springs within the casing between which said member operates, 85 said springs and contact surfaces being formed to impart a snap movement to said shaft after its initial, manually-induced movement, means establishing an electric circuit when said metallic and spring surfaces are in contact, and means on the sup- 90 port having transmission connections for initially moving said shaft.

5. In a device of the nature disclosed, a tool casing, a support external of the casing, 95 a rock shaft extending from the support to the interior of the casing, a polygonal mem- 100 ber on the inner end of the casing having alternate insulating and metallic contact surfaces, springs within the casing between which said member reciprocately rocks said springs and member co-operating to impart a snap movement to said rock shaft after its initial, manually-induced movement, means establishing an electric circuit when said metallic and spring surfaces are in contact, 105 a longitudinally reciprocating finger mem- 110 ber on the support having its opposite ends exposed on opposite sides of the support, and means converting the longitudinal reciprocating finger movement into a recipro- cal shaft rocking movement.

In testimony whereof, I have hereunto set my hand.

J. A. SMITH.
